UNITED STATES PATENT OFFICE.

LOUIS ROTH, OF NEW YORK, N. Y., ASSIGNOR TO STERLING BRONZE COMPANY, OF NEW YORK, N. Y., A CORPORATION OF NEW YORK.

THEATER CHAIR.

Application filed June 14, 1921. Serial No. 477,397.

To all whom it may concern:

Be it known that I, LOUIS ROTH, a subject of Austria-Hungary, residing at the city of New York, county of Bronx, and State of New York, have invented a certain new and useful Theater Chair, of which the following is a specification.

This invention is a chair for use in theaters, moving picture houses and auditoriums generally, and the object in view is to control the flow of a warming or cooling atmosphere within the aisle between adjacent rows of chairs.

In a prior application filed by me on May 20, 1920, Serial No. 382,731, there is disclosed one embodiment of means for directing the flow of air by way of a grill positioned at the lower part of a chair.

According to the present invention, the duct for the inflowing atmosphere is extended upwardly to the arm of the chair, and a plurality of grills are used, the area of the openings in said grills being equal substantially to the cross sectional area of the duct 25 for feeding the atmosphere whereby the flow of air into the aisle is unimpeded.

The invention embodies means for adapting the chair to the slope or level condition of the floor upon which said chair is to be installed, and to this end I employ a base in either of two forms in one of which the bottom portion is horizontal to suit a level floor, whereas in another form the base has an inclined lower portion the inclination of 35 which corresponds substantially to the slope of the floor.

Other functions and advantages of the invention will appear from the following description taken in connection with the drawings, wherein—

Figure 1 is a side elevation of a chair embodying the invention.

Figure 2 is a vertical cross section taken in the plane of the dotted line 2—2 of Figure 1.

Figure 3 is a horizontal cross section in the plane of the dotted line 3—3 of Figure 1.

Figure 4 is a detail view in side elevation of a form of the base adapted for a sloping floor.

A designates a chair frame which is usually of cast metal and of desired form, ornamental or otherwise. Said frame is skeletonized for the reception of an air distributing grill, the latter being composed, in the

example shown, of two parts, an upper grill part B and a lower grill part C. Each grill part is cast or otherwise formed in a single piece of metal, the same being provided with openings b for the free flow of air through the grill. The parts B C composing the grill are shaped and proportioned to fit within the skeletonized frame A, to which frame said grill parts are secured fixedly by appropriate means. The grill parts are, or may, be of an ornamental character, and the two parts are separately attached to the chair frame so that the meeting edges of said grill parts may have a desired relation, it being preferred to provide the upper grill part B with a hood c at the lower edge thereof, said hood extending crosswise of grill B and said hood projecting forwardly from the vertical plane of the grill, as shown in Figure 2. The chair frame is provided, as usual, with an arm rest D and with a chair back E, a seat F being hung between adjacent chair frames, in a manner well known to those skilled in the art.

The chair frame A may as usual rest upon the floor of the auditorium, but it is preferred to employ a base G to which the lower part of the chair frame is suitably attached. The base G is shown in Figures 1 and 2 as adapted to be secured to a horizontal floor, all parts of the base being equal in height, but it happens quite frequently that chairs are to be secured to sloping or inclined floors, in which event I employ a tapering base G', the lower floor line g of which is inclined to correspond with the slope of the floor, see Figure 4. The tapering base rests firmly upon the sloping floor and it affords a horizontal, or substantially horizontal, upper surface upon which rests the chair frame so as to occupy the required vertical position, it being understood that the base is fixedly attached to the floor and the chair frame is in like manner attached to the base.

H is a flue plate positioned within the limits of the chair frame and in facing relation to the grill parts therein so as to form a flue I. The flue plate is of channelled form in cross section, see Figure 3, the lower part of said plate being expanded or enlarged at h in order to register with the feeding flue I provided in the floor of the auditorium, see Figure 2. Said flue plate lies within the limits of the chair frame, ex-

tending upwardly to the arm rest D so as to have a compact relation to the chair frame and to the seat, see Figure 2, whereas the expanded lower part h of the flue plate 5 is in register to flue I, to permit the free flow of air into the distributing space, chamber or flue formed by and between the flue plate and the grill parts B C. The use of a grill in two parts and of a flue plate extending 10 substantially to the arm rest of the chair provides for the upward extension of the distributing space within the limits of the chair frame, and provision is thus made in the grill parts B C for openings b the 15 aggregate area of which is equal substantially to the cross sectional area of the flue space or of the flue I, whereby the metal grill B C affords no obstruction to the outflow of the current of air; but, on the contrary, the air is free to flow without impedance by the presence of the grill, the hood c of grill part B having a tendency to direct the inflowing air downwardly toward 20 the floor of the aisle.

25 Having thus fully described the invention, what I claim as new and desire to secure by Letters Patent is:

1. In a chair of the class described, the combination with a chair frame, of an imperforate flue plate extending from the floor line upwardly with respect to the chair frame and materially above the seat portion thereof, said flue plate having a lower portion inclined to the plane of the chair frame 30 and an upper portion in substantially parallel relation to said chair frame, and a plurality of grills in fixed relation to the chair frame and in opposing relation to the imperforate flue plate, the area of the opening 35 in the grill being equal substantially to the cross sectional area of a flue provided by and between the grill and the flue plate.

2. In a chair of the class described, the combination with a chair frame, of an imperforate flue plate extending from the floor line upwardly with respect to the chair frame and materially above the seat portion thereof, said flue plate having a lower portion inclined to the plane of the chair frame 40 and an upper portion in substantially parallel relation to said chair frame, and a plurality of grills positioned in substantially vertical alignment with each other and within the chair frame, one of said grills being 45 opposite to and parallel with the upper portion of said imperforate flue plate and the other of said grills being opposite to the lower inclined part of said imperforate flue plate.

60 3. In a chair of the class described, the combination with a chair frame provided with an arm rest, of an imperforate flue plate extending upwardly within the chair

frame substantially to the level of the arm rest, and a divided open-work grill positioned in facing relation to said flue plate, the upper part of the grill being provided at its lower portion with a hood which protrudes beyond the vertical plane of the grill. 65

4. In a chair of the class described, the combination of a hollow floor base the bottom edge of which is inclined according to the slope of the floor, a chair frame erected upon the floor base, a flue plate in communication with said hollow base extending upwardly from the floor line and within the limits of the chair frame, said floor base being separate from the chair frame and the flue plate, and an open-work grill secured to the chair frame in facing relation 70 to the flue plate. 75

5. A chair frame skeletonized for the reception of an air-distributing grill, and a grill composed of an upper part and a lower part, said grill parts being formed separately and having openings for the flow of air, the one part resting upon the other and the two parts fitted within said frame 80 and in facing relation to said grill parts, said flue plate being of channeled form in cross section with the lower part inclined and expanded opposite the lower grill part, said flue plate extended upwardly and materially above the seat portion of the chair, the area of the openings in the grill parts being equal substantially to the cross sectional area of the flue space between the 85 grills and the flue plate. 90

6. A chair frame skeletonized for the reception of an air-distributing grill, and a grill composed of an upper part and a lower part, said grill parts being formed separately and having openings for the flow 95 of air, the one part resting upon the other and the two parts fitted within the said frame, and separately attached thereto, and a flue plate positioned within the limits of the said frame and of channeled form in cross section with the lower part inclined and expanded opposite the lower grill part, said flue plate being extended upwardly and materially above the seat portion of the chair, the area of the openings in the grill 105 parts being equal substantially to the cross sectional area of the flue space between the grills and the flue plate, the upper grill part being provided at its lower edge with a hood 110 at a point opposite the upper part of the inclined wall of the flue plate and extended 115 beyond the plane of the top of the lower grill part. 120

In testimony whereof I have hereto signed my name this 7th day of June, 1921.

LOUIS ROTH.
